UNITED STATES PATENT OFFICE.

HENRY B. MEINHARDT, OF CHICAGO, ILLINOIS.

REFRIGERATOR-CAR PARTITION.

Application filed June 29, 1927. Serial No. 202,185.

My invention relates in general to refrigerator car partitions.

It relates more in particular to a removable and adjustable partition designed to be shipped in bundle form to the point of use, and/or readily and quickly placed in a car to segregate a portion thereof.

Refrigerator cars employed in the shipment of perishables are iced in the summer and heated in the winter and normally two bulkheads or ice compartments one at each end are employed so that the temperature of the entire car is moderated. Very often only a small part of the car is loaded with perishables and it is somewhat of an expense to ice the entire car for a small shipment of freight in one end thereof. Partitions for refrigerator cars have been put in use to solve this difficulty, so that only one end of the car would have to be iced, but this scheme has not worked out because the partitions were semi-permanent and there was no flexibility such as was required when the size of shipments varied. Shippers would often rip out partitions when they received a partitioned car and needed the full car capacity.

The object of my present invention is a provision of a removable portable partition for a refrigerator car.

Another object is to provide a partition which can be placed in a car quickly, or with the same speed removed and made into bundle form for shipment.

Another object is to provide a removable partition which permits ready access to a car but which may be quickly secured together to close the same.

Another object is to provide a curtain which is easily adjusted to different sizes of cars.

In one embodiment of my invention, I provide a two part partition consisting of a pair of fabric curtains, preferably a fairly heavy grade of duck. Reinforced marginal edges are provided for securing the two curtains to the ceiling and side walls of the car in overlapping relation, with adjustable means for securing the overlapping portions together. A special type nail is provided and a pocket for holding the nails when the curtains are shipped, a pair of cords fastened on the back of one of the curtains facilitating the formation of a self-contained bundle.

Other objects and features of the invention will become apparent from a consideration of the following detailed description

taken with the accompanying drawings, wherein

Fig. 1 is a section through a refrigerator car showing my partition in elevation; 60

Fig. 2 is a longitudinal section through a refrigerator car along the line 2-2 of Fig. 1;

Fig. 3 is a plan view of the left-hand or first applied curtain; 65

Fig. 4 is a plan view of the complementary curtain;

Fig. 5 is an enlarged fragmentary view showing the means for fastening the curtains together; 70

Fig. 6 is an enlarged fragmentary section along the line 6-6 of Fig. 1;

Fig. 7 is an enlarged fragmentary section along the line 7-7 of Fig. 1, and

Fig. 8 is a perspective view of the partition when rolled into bundle form. 75

The invention is adapted to be applied to the usual form of refrigerator car 10 having an ice bunker 11 at the end thereof adapted to hold ice 12 for lowering the temperature 80 of the car for the protection of perishables. The car is provided with the usual center doors (not shown) and a bunker for ice is of course provided at each end. The car has the usual outer wooden frame with proper insulation, and the inside has a ceiling 13 with side walls 14 and 15 and floor racks 16 on which the shipment is placed. My improved partition is adapted to be secured across the car and fastened by nailing or 85 otherwise to the ceiling and side walls thereof.

The partition consists of two curtains 17 and 18, which are provided with a number of appurtenances to facilitate their being secured to the car, and also permitting them to be rolled into bundle form easily when removed therefrom. The curtains 17 and 18 shall designate as left and right hand curtains respectively. These curtains are shown 100 in Figs. 3 and 4 and will now be described in detail.

Each of the curtains has a reinforced upper margin 21 and 22, the reinforcement therein being in the form of a flat bar 23 of 105 spring material with apertures 24 which coincide with apertures in the fabric to form nail holes for the application of the curtains to the ceiling.

The outside edges of the curtains are provided with reinforced margins 25 and 26 which are formed from a number of thick-

nesses of fabric with leather tabs 27-27 secured by sewing or the like at regular intervals thereon. At the center of each one of the leather tabs, a nail hole 28 is provided 5 facilitating the application of the outside marginal edges to the inner side walls of the refrigerator car. The corners where the upper and side edges coincide are cut away in the manner shown so that when the 10 margins are turned at right angle to the curtains for application to the inside of the car, the corners of the curtains will fit snugly in the eave corners of the car. The curtains are reinforced by arcuate strips 29 at these 15 corners to prevent tearing of the fabric when a strain is placed thereon.

At the bottom of each one of the curtains making up the partition, are separate flaps or aprons 31 and 32 which are sewed to the 20 bottom of the curtains proper in the manner illustrated. The curtains themselves are dimensioned so that they do not touch the floor of even the lowest car, and accordingly only the flaps are in contact with the floor 25 or floor racks where they are apt to be injured or worn. The flaps are of sufficient length so that in the highest ceiling car they will trail on the floor racks, and accordingly a good air seal is obtained at the bottom of 30 the partition without exposing the curtains proper to excessive deterioration. When the flaps are worn or rotted, they are of course removed and new ones applied, so that one set of curtains will usually outlive several 35 sets of flaps.

The difference in the width of cars make it necessary to provide adjustable fastening means for securing the curtains together at their intersection. For obtaining this 40 result, I provide hooks 33 on the right hand curtain with a number of eyes 34 disposed in a transverse row in association with each one of the hooks on the left hand curtain. The hooks 33 are fastened at one end of a 45 spring 35, the other end of the spring being secured to a tab 36 secured to a reinforced portion 37 of the fabric. A shield or guard 38 preferably made of fabric and sewed to the reinforcing strip 37, holds the 50 spring in position so that at all times it will lay along the reinforcing strip 37. A non-elastic strand such as a chain 39 is secured within the spring, to the same members to which the ends of the spring are secured. 55 This chain permits the spring to be extended a sufficient distance to obtain a resiliently tight engagement between the curtains, but prevents the spring from being extended far enough to exceed the elastic limit of the material therein.

Any suitable fastening means such as 60 nails or screws, may be employed to secure the curtains to the ceiling and side walls of the car but I have made use of a special nail 65 41 having the usual head 41^a with an inner

head or stop 41^b. The stop 41^b limits the degree of insertion of the nail, and at the same time regulates the insertion so that a tight engagement will always be obtained. The workman applying the nails simply drives 70 them in as far as possible and the head 41^a is always left exposed so that a pulling tool can easily encircle the head for the purpose of removing the nails when the curtains are taken down. I provide a pocket 42 having 75 a closing flap 43 on the left hand curtain for holding the nails which are required to fasten the curtains to the car.

It often happens that after the curtains are placed into position, it is necessary to 80 go into the end of the car which is partitioned off, either to add or remove some of the perishable freight. To facilitate such movement, I provide hooks 44 on each one of the curtains near the outside edge thereof, 85 with an inserted eye 45 at each one of the inside edges of the curtains, so that the lower portions of the curtains may be hooked back in the manner indicated schematically in 90 Fig. 1.

When the curtains are removed from the car (following a technique which I will hereinafter describe) they are rolled up into 95 bundle form and fastened together. For this purpose, I provide fastening cords 46 and 47 secured to reinforced portions of the right hand curtain with hook members 48 and 49 at the free ends thereof. Rings 51 and 52 also secured to the reinforced portions 100 of the curtain are adapted to receive the hook members when the cords 46 and 47 are placed around the rolled or bundled curtains, and the curtains are then held in a 105 form to be shipped without the necessity of using any fastening means which do not constitute a part of the curtains themselves.

When the curtains are placed in position in the car, the left hand curtain is first 110 placed in position with the upper reinforced margin 21 facing toward the ice bunker, and the fasteners are nailed with the strip at the top only. Now the right hand curtain is placed against the left hand curtain but with its margin 22 facing away from the ice bunker so that the two curtains are brought 115 close together and it is fastened to the ceiling only, so that first both curtains are fastened to the ceiling alone. When they have been so fastened and are found to hang evenly, the side margins are then nailed to 120 the sides of the car. The flaps or aprons 31 and 32 are disposed in proper position on the floor racks so as to close up the bottom, and the curtains are fastened in the 125 center by connecting the hooks 33 to the proper rings 34, depending upon the width of the car in which the curtains are applied. If it is necessary to go into the portion of the car which is partitioned off by the curtains, the hooks 33 are removed and eyes in 130

the inside edge of the curtains are hooked back in the hooks 44.

Now assume that the car has been shipped to a destination where the partition will 5 not be required. The partition is then removed from the car and sent either back to a central point or to some other destination previously decided upon.

In removing the partition, the following 10 technique is observed:

The curtains are first disconnected from each other, and the side nails then removed and placed in the pocket, the curtains then 15 hanging free from the ceiling. Now the nails are removed from the top of the right hand curtain, and this curtain is laid out flat with the fastening cords 46 and 47 underneath, so that the curtain will appear in the manner shown in plan in Fig. 4. The nails 20 are then removed from the top of the left hand curtain and this curtain is placed on top of the right hand curtain with the pocket up, and with the reinforced margin 21 coinciding with the margin 22 on the first laid 25 curtain. Now the curtains are picked up together at the bottom and folded over in the center so that the flaps 31 and 32 together overlie the upper margins of the curtains. The curtains are now rolled together around 30 the reinforcements 21 and 22 so that these parts of the curtains constitute the core or center of the bundle. When the curtains are 35 fully rolled, the fastening cords will be found on the outside of the bundle, so that it is necessary simply to pass them around the bundle and fasten the hook members in the rings 51 and 52. As the curtain is already stenciled so that its shipping destination appears on the outside of the bundle, it 40 is now ready for shipment without the necessity of adding a tag or taking any other precautions whatsoever.

To facilitate handling of the curtains, I 45 stencil on the face thereof, full directions as to how the curtains are to be used, how they are to be applied, and how taken down. I find that not only are these instructions 50 beneficial but they add distinguishing marks to the fabric of which they are made so that unscrupulous workmen will not be tempted to remove portions thereof for their own purposes.

It is obvious that the materials going into the curtain may vary depending upon the 55 ideas of those using them. I have obtained the best results with a fairly heavy duck for the main part of the curtain with a somewhat lighter duck for the flaps at the bottom. The metal parts are made of rust-proof steel, 60 and the strips 23 are of spring steel. This prevents bending of this reinforcing strip out of its proper plane, but if by any chance it should be bent, it will spring back to normal and no damage will result. The reinforcing tabs 27, I have made of leather but 65

of course other material such as batting fabric could be substituted. I refer in the claims to fabric curtains but I do not limit myself to what is generally considered fabric, but I include any material such as rubber sheeting or the like which would be flexible enough for use in the manner described.

An advantage of my curtain partition will be apparent when a typical condition is 70 considered. On a hot summer day a small shipment of perishables requiring refrigeration and a relatively large shipment of non-perishable freight which has absorbed a great amount of heat are to be shipped from 80 point A. They can all be loaded in the same refrigerator car, but the ice required to reduce the temperature of the non-perishable freight (which would have to be done before the small quantity of perishable freight 85 would receive any benefit from the refrigeration) is enormous. Even this is preferable however, to the use of two cars, viz a refrigerator car for the perishables and an ordinary box car for the non-perishables, 90 and under these conditions probably the whole car would be iced, and used to carry all the freight, perishable and otherwise, from that particular point. The amount of ice used would be very great, and the perishables would not receive the best possible 95 protection.

With my curtain partition, one end of the car only will have to be iced, and my removable partition employed to segregate the 100 perishable freight. The non-perishable shipment can then be loaded in the remaining portion of the car, where the heat confined therein will have little or no effect on the temperature of the partitioned off 105 iced end of the car. As a matter of fact, I have found by actual experiment under similar circumstances, that I can partition off one end of a car and obtain better temperature control and a lower temperature with less 110 than half the ice (or fuel) in one end of the car then can be obtained with a full car of perishables with both ends iced and no curtain used.

Although I have described my invention 115 as applied only to refrigerator cars, it is obvious that it may be used in many analogous places, for example partitioning off a portion of an automobile truck used for long distance hauling. Other possibilities will 120 readily suggest themselves to those acquainted with the art, and for this reason I do not confine myself to the details or to the use described, and the invention is limited only by the scope of the appended 125 claims.

What I claim as new and desire to secure by United States Letters Patent is:

1. A refrigerator car partition comprising a pair of fabric curtains, means for securing 130

- the top and one side of each of the two curtains to the ceiling and side walls of the car, a hook secured by flexible means to one curtain and a plurality of hook engaging members on the other curtain in association with each hook, so that the curtains may be secured in refrigerator cars of varying sizes, and in each instance, the two curtains secured taut in overlapping relation.
10. 2. A partition as defined in claim 1 with a hook secured to the outside margin thereof and a ring secured to the inner margins so that said curtains may be hooked back to furnish access to the enclosed portion of the car.
15. 3. A refrigerator car partition comprising a pair of fabric curtains, reinforced upper and lateral marginal edges thereon for nailing to the ceiling and side walls of the car, and means for securing the curtains together at their intersection.
20. 4. A partition as defined in claim 3 wherein the upper reinforced marginal edges of the two curtains face in opposite directions and away from each other, so that the curtains when in overlapping relation may be brought close together.
25. 5. A partition as defined in claim 3 wherein said curtains have a separate apron sewed to the bottom thereof adapted to rest on the car floor to prevent the passage of cool air between the bottom of the curtains and the car floor.
30. 6. A partition as defined in claim 3 wherein said curtains are secured to the car by special nails driven through the reinforced edges thereof, and a pocket is provided on the face of one of said curtains for holding said nails when the curtains are removed from the car.
35. 7. A partition as defined in claim 3 wherein curtains are fastened to the inside of the car by special nails, with a pocket on the face of one curtain to receive the nails, and fastening means on the reversed side of the other curtain for securing the curtains in bundle form when removed from the car.
40. 8. A partition as defined in claim 3 wherein said curtains are secured together in overlapping relation by hooks and eyes, at least one of which is secured to the curtain by flexible means.
45. 9. A partition as defined in claim 3 wherein said curtains are secured together in overlapping relation by hooks and eyes, at least one of which is secured to the curtains by a flexible element, with a non-flexible strand for preventing overstressing of said flexible element.
50. 10. A refrigerator car partition formed of suitable fabric comprising a pair of fabric curtains with means for securing said curtains across the interior of a refrigerator car, means secured to one of the curtains for holding the pair of curtains in bundle form when removed from said car, said means for securing the curtains in bundle form includes a pair of strands having hooks at the end thereof and eyes at the place where they are secured to the curtain, the strands adapted to be extended around the rolled fabric partition, and the hooks adapted to engage in the eyes.
55. 11. A refrigerator car partition comprising a pair of fabric curtains, an upper marginal edge on each curtain reinforced with a flat spring steel bar, with holes therein for nailing the curtains to a car ceiling, means for securing the curtains to the side walls of the car, and means for securing the curtains together in overlapping relation.
60. 12. A refrigerator car partition comprising a pair of fabric curtains secured to the top and side walls of the car and releasably secured together in overlapping relation, the curtains extending almost to the floor of the car and having separate flaps or aprons for extending to the car floor and lying partly thereon for closing the space between the floor and the bottom of the partition, the flaps being replaceable when worn or otherwise unsuited for further use.
65. In witness whereof, I hereunto subscribe my name this 26th day of May, 1927.
- HENRY B. MEINHARDT.
